UNITED STATES PATENT OFFICE.

HARVEY E. FRY AND WALTER O. KEITER, OF LOCKPORT, NEW YORK.

POWDER-PUFF.

1,349,057.

Specification of Letters Patent. Patented Aug. 10, 1920.

Application filed March 28, 1919. Serial No. 285,716.

To all whom it may concern:

Be it known that we, HARVEY E. FRY and WALTER O. KEITER, citizens of the United States, residing at Lockport, in the county 5 of Niagara, State of New York, have invented a new and useful Powder-Puff, of which the following is a specification.

This invention relates to a powder puff, one of its objects being to provide a simple 10 and attractive device of this character which can be manipulated readily, and is cheap to manufacture.

With the foregoing and other objects in view, which will appear as the description 15 proceeds, the invention resides in the combination and arrangement of parts and in the details of construction hereinafter described and claimed, it being understood that, within the scope of what is claimed, changes in the 20 precise embodiment of the invention shown can be made without departing from the spirit of the invention.

In the accompanying drawings the preferred form of the invention has been shown.

25 In said drawings:

Figure 1 is a plan view of the device.
Fig. 2 is a side elevation thereof.

Referring to the figures by characters of reference 1 designates a thickness of fibrous 30 material which can be wool or any other desired material matted together and fastened to one side of an intermediate layer of chamois or other desired material, indicated at 2. As shown in the drawing the margin of

the interposed layer 2 can be scalloped. An- 35 other thickness of fibrous material, such as wool, is indicated at 3, and is located upon the layer 2. This top thickness 3 is embraced by a ribbon 4 or the like the ends of which are preferably tied together to form 40 a bow which enables the ribbon to be used as a grip whereby the device can be held readily while in use.

By having the interposed thickness 2 of chamois or the like, the device is preserved 45 in proper shape. The upper thickness 3 of fibrous material serves as a yielding backing for the ribbon so that when said ribbon is grasped by the user, it will be held sufficiently taut by the fibrous material to allow 50 the powder puff to be manipulated easily.

What is claimed is:

A device of the class described including a disk of chamois, a substantially circular puff 55 of wool affixed to each surface of the disk and concentric therewith, and a band secured between the disk and one of the puffs and extending diametrically across said puff to form a finger receiving loop, the ends of the band being detachably connected. 60

In testimony that we claim the foregoing as our own, we have hereto affixed our signatures in the presence of two witnesses.

HARVEY E. FRY.
WALTER O. KEITER.
